UNITED STATES PATENT OFFICE.

JOSEPH M. SEGUR, OF ADRIAN, MICHIGAN.

HAND CORN-PLANTER.

SPECIFICATION forming part of Letters Patent No. 427,625, dated May 13, 1890.

Application filed February 13, 1890. Serial No. 340,352. (No model.)

To all whom it may concern:

Be it known that I, JOSEPH M. SEGUR, a citizen of the United States, residing at Adrian, county of Lenawee, State of Michigan, have 5 invented a certain new and useful Improvement in Hand Corn-Planters; and I declare the following to be a full, clear, and exact description of the invention, such as will enable others skilled in the art to which it pertains 10 to make and use the same, reference being had to the accompanying drawings, which form a part of this specification.

In the drawings, Figure 1 is a front elevation of the corn-planter embodying my invention. Fig. 2 is a longitudinal central sectional view of the same. Fig. 3 is a separate view illustrating how the door is hinged to the top of the hopper. Fig. 4 is a cross-sectional view through the stop-plate. Fig. 5 is 20 an enlarged view showing the relative position of the seed-cup and its cut-off when the plunger is at the top of its stroke. Fig. 6 is an enlarged front view of the cut-off and its spring.

25 It is the purpose of my invention to produce a hand corn-planter which shall possess certain novel features of construction; and it consists, first, in novel and convenient means for hinging the lid to the top of the hopper; second, in 30 novel and efficient means for limiting the upward and downward stroke of the plunger; third, in a novel spring arrangement whereby the seed cut-off is poised in its place, so that it may yield freely in a direction from side to 35 side and longitudinally of the cut-off, while at the same time it may be pressed outward or yield to the pressure of the grain from within the seed-cup.

In carrying out my invention, A represents 40 the standard, and B the seed-hopper, of the planter embodying my invention.

C represents the plunger; D, the plunger-rods; E, the seed-cup; F, the cut-off, and F' the cut-off spring.

45 At the top of the hopper B is a lid B', hinged to turn outward about its outer edge.

In order to form a suitable hinge-rod, I employ a wire b, which is bent at its extremities to form arms b', and at the ends of these arms 50 they are bent outwardly or inwardly, as shown at b'', whereby the said hinge-rod is held firmly in its place by the bent end coming against

the metal of the hopper. The nipple at the top of the hopper is turned over this wire, which gives to the hopper at this point the 55 requisite strength and finish. This construction affords a ready means for hinging the lid, which is very effectual and makes a cheap and durable construction.

d represents the bends or kinks in the 60 plunger-rods D, and D' represents the stop-plate, which is held in place by one or more bolts or fastenings d', which unite it with the standard. This plate and the bends d are so disposed with relation to each other 65 that as the plunger is moved up or down these bends or kinks, coming into contact with the plate, will limit the motion of the plunger in either direction. This forms a very effectual stop contrivance for limiting 70 the throw of the plunger.

The cut-off spring F' is constructed as shown in the drawings. It is made in corrugated form—that is to say, it is bent upon itself two or more times between its middle 75 and each extremity.

As shown at f, the extremities are united by screws or otherwise to the standard. The spring lies flat across the standard and the top of the cut-off F, and the cut-off is fastened to the middle loop or corrugation of the spring by a screw or bolt and washer f'. Now, it is apparent that this seed-cup may be 80 adjusted longitudinally with respect to the spring by simply loosening the said bolt or screw f'. This spring F', constructed as above described, has a very peculiar action. Its middle portion is flexible in all directions—that is to say, it permits the cut-off to vibrate, if necessary, in a longitudinal di- 85 rection, and also permits it to vibrate lat- 90 erally if it should be so impelled, while at the same time any pressure of grain from beneath will lift its upper end, so as not to crush the grain, and this is accomplished by reason of there being at least two or more corrugations or folds in the wire between the middle and each extremity of the spring.

Two complete loops upon each side of the middle one are sufficient for the usual purposes; but if it is desired to be adjusted still more sensitively an additional loop may be employed on each side, or more loops, if necessary.

Heretofore it has usually been customary to adjust the upward motion of the plunger with respect to the seed-cup so that when the plunger is at its uttermost limit the seed-cup shall have passed completely beyond the cut-off. The result of such a construction in practice is that when the plunger is again forced downward some of the corn in the bottom of the seed-cup may become clogged 5 against the cut-off just as the plunger begins to descend and results in the cut-off forcing the said clogged kernels upward, and may completely empty the seed-cup, causing it to descend with a portion only or none of its 10 charge. I overcome this difficulty as follows: I adjust the throw of the plunger with respect to the seed-cup and its cut-off so that when the seed-cup is at its uppermost point it will have only partially passed upward by the 15 cut-off, leaving the cut-off at such a point as to partially close the seed-cup, but at the same time leaving enough opening into the seed-cup above the cut-off to permit the corn or seed to easily enter and fill the cup. Now, 20 when the plunger descends, the only kernels or grains that can by any possibility become clogged with the cut-off will be those close at the top of the seed-cup, and should any such kernel be expelled by the cut-off it cannot result in carrying out the other grains from the 25 seed-cup. This arrangement insures that each descent of the plunger will carry substantially a full charge of seed in the seed-cup.

The spring arranged to admit of longitudinal 30 and lateral as well as outward vibrations of the cut-off greatly assists to prevent it from becoming clogged with any grain, since these longitudinal or lateral vibrations will serve to shift the kernel and enable it to assume a position disengaged from the cut-off.

What I claim is—

1. In a hand corn-planter, the combination, with the hopper, of a lid hinged at its outer edge upon a hinge-rod, said rod consisting of 35 a wire extending across said outer edge, thence backward along each side of the hop-

per, and with its extremities turned through the metal of the hopper to hold it in place, substantially as and for the purposes described. 50

2. In a hand corn-planter, the combination, with plunger-rods D, of bends or shoulders d and a stop-plate D', fastened to the standard and with its ends engaging said plunger-rods, substantially as and for the purposes described. 55

3. In a hand corn-planter, the combination, with its cut-off, of a flat corrugated spring F', said spring fastened at its middle to the cut-off and at its extremities to the standard or 60 adjacent parts, and having two or more loops of its corrugations interposed between the middle and each extremity of the spring, substantially as and for the purposes described.

4. In a hand corn-planter, the seed-cup and 65 cut-off and means for actuating the seed-cup, the travel of said seed-cup being so adjusted with respect to the cut-off that at the uppermost point of its travel the cut-off shall remain partly over the seed-cup, substantially as and 70 for the purposes described.

5. In a hand corn-planter, the combination, with a seed-cup and means for actuating the same, of a yielding cut-off arranged in such 75 position with respect to the seed-cup that it shall partly cover the seed-cup when the latter is at the top of its stroke, substantially as and for the purposes described.

6. The combination, with a hand corn-planter, of a cut-off poised in position by a 80 spring to which it is attached, said spring adapted to permit vibrations longitudinally and laterally of the cut-off and to yield outwardly to a pressure of seed from within, substantially as and for the purposes described. 85

In testimony whereof I sign this specification in the presence of two witnesses.

JOSEPH M. SEGUR.
